UNITED STATES PATENT OFFICE

GUSTAVE E. VILLARET, OF LEONIA, NEW JERSEY, ASSIGNOR TO LIGHTING APPLIANCE COMPANY, INC., OF NEW YORK, N. Y.

DESIGN FOR A LIGHTING FIXTURE SHADE OR ARTICLE OF SIMILAR NATURE

Application filed April 1, 1931. Serial No. 39,322. Term of patent 3½ years.

To all whom it may concern:

Be it known that I, GUSTAVE E. VILLARET, a citizen of the United States, residing in Leonia, in the county of Bergen and State of New Jersey, have invented a new, original, and ornamental Design for a Lighting Fixture Shade or Article of Similar Nature, of which the following is a specification, reference being had to the accompanying drawing, forming a part thereof.

Fig. 1 is a front elevational view of a lighting fixture shade showing my new design. The portions shown in dotted lines

are mere repeats of those shown in full outline.

Fig. 2 is a diagrammatic outline of the side.

Fig. 3 is a perspective view thereof.

Fig. 4 is a diagrammatic outline of the bottom.

I claim:

The ornamental design for a lighting fixture shade or article of similar nature, as shown and described.

In testimony whereof I affix my signature.
GUSTAVE E. VILLARET.
